United States Patent Office.

WARREN P. MILLER, OF SAN FRANCISCO, CALIFORNIA.

Letters Patent No. 70,786, dated November 12, 1867.

IMPROVEMENT IN FAN-BLOWERS.

The Schedule referred to in these Letters Patent and making part of the same.

TO ALL WHOM IT MAY CONCERN:

Be it known that I, WARREN P. MILLER, in the city and county of San Francisco, and State of California, have invented a new and improved Mode of Constructing Spiral Fan-Blowers; and I do hereby declare that the following is a full and exact description thereof, reference being had to the accompanying drawings, and to the letters of reference marked thereon, making part of this specification, in which—

Figure 1 is a side elevation, with a portion of the case of the fan-wheels broken away, thus showing the position of the fans, and the arrows point their direction; also the direction of the air-currents.

Figure 2 is a horizontal section cut through the centre of the shaft.

Letters *a a* is the frame or bed-plate; letters *b b*, boxes for the support of the shaft; *c c*, the principal shaft; *d d*, a hollow shaft turning on shaft *c*; letter *e*, pulley on shaft *c*; letter *f*, pulley on shaft *d*; letters *g g*, wheel on hollow shaft *d*, carrying a double set of fans; letters *h h*, wheel on shaft *c*, carrying one set of fans; letters *i i i i* the fans; letters *j j*, outside case of fan-wheels; letters *k k k*, supports for the frame; letters *l l*, screw abutment for shaft *c*; letters *m m*, conical case for the air-duct.

To enable others skilled in the art to make and use my invention, I will proceed to describe its construction and operation.

I construct the fan-wheel thirty inches in diameter, set the fans at an angle of about forty degrees with the line of motion. The shaft *c* is set in suitable boxes, and supported by the abutment *l*, and carries one set of fans, which are set in reverse position to those on wheel *g*, and also turn in the opposite direction to which said wheel *g* turns.

By reference to the drawings it will be observed, that if the wheels *g* and *h* are set in rapid motion in the directions indicated, by the application of belts to the pulleys *e* and *f* the air will be impelled into the duct *m*.

The object of the above-described arrangement of fans is to produce a stronger current of air, for all purposes to which fans are applicable, than can be effected with a single wheel.

The result is produced in manner, to wit: A partial vacuum being formed behind each fan of the preceding wheel, the compressed air in front of the fans of each succeeding wheel will escape into the vacuum before mentioned, and thus each wheel acts as a feeder to the wheel preceding it.

What I claim as my invention, and desire to secure by Letters Patent, is—

A blower, consisting of two or more wheels, constructed and operated in manner as described.

WARREN P. MILLER.
